UNITED STATES PATENT OFFICE.

HERMANN LEMP, OF LYNN, MASSACHUSETTS, ASSIGNOR TO GENERAL ELECTRIC COMPANY,
A CORPORATION OF NEW YORK.

DOUBLE-TANK FUEL SYSTEM.

No. 922,604.

Specification of Letters Patent. Patented May 25, 1908.

Application filed August 1, 1904. Serial No. 219,010.

To all whom it may concern:

Be it known that I, HERMANN LEMP, a citizen of the United States, residing at Lynn, county of Essex, State of Massachusetts, have 5 invented certain new and useful Improvements in Double-Tank Fuel Systems, of which the following is a specification.

My invention relates to fuel systems of the double-tank type in which the main tank or 10 source of supply is preferably at or about atmospheric pressure and fuel is supplied therefrom to the burner at the desired working pressure by means of a power pump. The fuel in the auxiliary tank, which may or may 15 not be initially supplied from the main tank by gravity feed or otherwise, is preferably maintained under a pressure suitably higher than that of the atmosphere, but much less than the working pressure, so that fuel will 20 be fed automatically to the burner, and at a pressure which is sufficient to maintain the flame in a banked condition. Such a system is particularly applicable to automobiles, in 25 which class of service it is desirable to dispense with a high initial pressure on the fuel, with its attendant liability to explosion or fire in case of accident or leakage of the system, especially when any of the more volatile fuels are employed.

30 The object of my invention is to provide a simple and convenient means for recharging the auxiliary tank with fuel from time to time as occasion demands.

Hitherto it has been necessary in order to 35 replenish the supply of fuel in the auxiliary tank, first to remove the pressure on the fuel by allowing the compressed air to escape from the tank, then to supply the fuel in any approved manner, as for example by feeding 40 it from the main tank under gravity, and after the desired quantity has been supplied to again place the tank under pressure, as by means of air supplied by a hand pump, or furnished from a reservoir containing compressed air. Manifestly this process is attended 45 with much inconvenience to the operator, especially when it is necessary to place the tank under the initial pressure by using a manually-operated pump, while on the 50 other hand to employ compressed air necessitates a storage tank which is also objectionable because of the space required to accommodate it and also the extra weight, both of which are important considerations in auto-

mobile power apparatus. With my invention, however, the refilling process is much simplified. In practice I provide a connection extending from the auxiliary tank to the main service pipe at a point between the power pump and the burner, and make use 55 of the pump for recharging the auxiliary tank from the main source of supply. As the pump is capable of delivering fuel at a pressure much higher than that on the auxiliary tank, the air contained in the latter 60 does not have to be released, as the superior pressure due to the pump will force the fuel into the tank against the pressure of the air 65 therein. This supply connection is controlled preferably by a valve which is conveniently 70 accessible to the operator, so as to be manipulated from the vehicle seat. With this arrangement it simply remains for the operator to open the valve when the fuel is low and the pump then delivers fuel to the tank at 75 the same time of delivering to the burner. When the quantity is restored to normal the valve is again closed.

With a given initial pressure on the auxiliary tank, it is apparent that the pressure 80 will vary with changes in the quantity of fuel contained in the tank; therefore, by means of a pressure gage the pressure of the air may serve as a satisfactory guide to the operator for indicating the quantity of fuel 85 in the auxiliary tank at any given time, in view of the complementary relation existing between the quantity of fuel and the pressure of the air. Thus when the air pressure is indicated to be low the valve in the 90 supply connection may be opened to permit fuel to pass to the tank, and when sufficient fuel has been supplied to cause the pressure to attain its normal value, as is indicated by the gage, the supply may be cut off by closing the valve. If for any reason the pressure on the auxiliary tank should become 95 excessive, a portion of the fuel may be drawn off by opening the gravity feed connection between the main and auxiliary 100 tanks, thereby causing fuel to flow from the latter to the former, by virtue of the relative difference of pressure between them.

The refilling may be done at any time during operation of the vehicle, but it is better 105 practice to recharge the auxiliary tank when the conditions of service are such that the pump is not working at its full capacity, as

when the load on the vehicle is light and the demand for thermal energy is correspondingly reduced. At such times the pump may deliver both to the burner and to the tank without seriously affecting the heating of the boiler.

In the accompanying drawing, which illustrates one embodiment of my invention, is diagrammatically shown my improved 10 fuel system in connection with steam power apparatus suitable for automobiles.

Referring to the drawing, 1 represents conventionally a flash boiler which receives water at the inlet 2 and delivers it as super-heated steam to the engine 3, through the' 15 pipe 4, which is controlled by the throttle 5. In the present case the exhaust steam from the engine is used for inducing a forced draft and is discharged through the pipe 6 20 into the down-draft flue 7 which connects with the interior of the casing of the boiler. Situated below the boiler in the bottom of the casing 8 is a burner 9 which heats the boiler, and the products of combustion pass 25 from the casing either through the up-draft flue 10 when the demand for steam is light and the forced draft is not operating; or through the down-draft flue 7 when the apparatus is working and the exhaust is in- 30 ducing a forced draft. I have elected to show a single burner of the jet type, but it is to be understood that my invention is not limited thereto, as another type of burner or separate main and auxiliary burners may be 35 used equally well in carrying out the invention in some of its aspects.

Two separate sources of fuel supply are essential to my invention. One of the sources is adapted to supply fuel to the burner at a 40 suitable pressure above atmosphere, say ten pounds per square inch, which produces a flame of sufficient volume to maintain the boiler in a heated condition, or in other words to support a pilot flame when no steam, or 45 only a small amount, is demanded. The main fuel supply is derived from the other source which is preferably at atmospheric pressure, and by means of a power pump the pressure is increased to about sixty pounds 50 per square inch, which pressure is capable of maintaining the main operating flame. The main tank 11 is situated slightly above the tank 12 in order that it may supply fuel to the latter by gravity, the pipe 13, which is 55 controlled by the valve 14, being provided for this purpose. The tank 12 is provided with a level or overflow pipe 15 having a stop-cock 16, and is also provided with a pressure gage 17, which is connected with 60 the tank by the air-supply pipe 18. Attached to this air-supply pipe is a manually-actuated pump 19 by which an initial air pressure may be placed on the tank. In initially filling the tank the valve 16 of the overflow pipe 15 is opened so as to permit the air con-

tained in the tank to escape as fuel enters the same through the gravity feed connection. The fuel is allowed to flow until it has attained the level of the overflow pipe 15 and is seen to overflow and discharge from 70 the cock 16, when the valve 14 is immediately closed to cut off the flow from the main tank. Following this the stop-cock of the overflow pipe is closed and the fuel is then placed under air pressure by the air pump. 75

The main supply of fuel to the burner is delivered through the pipe 20 by means of the power pump 21. This pump is or may be of the variable stroke type and tends to automatically maintain the fuel supply at 80 substantially constant pressure. The driving mechanism therefor comprises an eccentric 22 which may be mounted on the axle of the automobile or other rotating part and may operate continuously or otherwise as desired. 85 The eccentric is connected to the piston 23 of the pump by a suitable cross-head frame 24 in such a manner as to permit of lost-motion under certain conditions. The eccentric imparts a constant length of stroke in one 90 direction and operates to move the piston out of the pump cylinder, while a suitable elastic means, such for example as springs 25, impart a stroke in the opposite direction and of a length which may vary as the fuel 95 pressure on the piston tends to exceed a predetermined amount. The springs are shown fixed at one end relative to the pump cylinder and are secured at their opposite ends to the moving abutment 26, which is rigidly 100 connected with the pump piston. The rods 27 of the cross-head frame extend freely through openings 26' in the abutment and are adapted to engage at their ends with the abutment to move the piston outwardly. 105 This construction permits the cross-head frame to move through its full stroke irrespective of the length of stroke of the piston due to the action of the springs. These springs are of such strength that a pressure 110 of substantially sixty pounds per square inch may be maintained on the fuel supplied to the burner, and any tendency of the fuel to rise above such pressure is compensated for by their yielding to a greater or less degree so as to alter the effective stroke of the pump. Any equivalent means may be employed for accomplishing this result as my invention is not specifically directed to this feature. It may also be desirable to have the fixed ends of the pump springs attached to an adjustable device capable of manipulation from the vehicle seat, whereby the tension of the springs, and consequently the working pressure due to the pump, may 115 be varied at will to suit different conditions of service. 120

The flow of fuel from the auxiliary tank takes place through the pipe 28 which communicates with the main supply pipe, and is 130

controlled by a valve 29. The opening and closing of this valve bears a definite relation to the main fuel supply and to the forced draft; that is to say, as to the former, it should be opened immediately upon cessation of the main supply, to preserve the continuity of the flame in order to obviate the necessity of relighting, and it should be closed as soon as the engine is started so that fuel will not be shunted relatively to the burner and be delivered to the auxiliary tank. In order to obtain this relationship, I find it convenient to connect the auxiliary supply valve with the steam throttle, since, in the present case, the main supply pump is driven by the engine which operates only when the throttle is open. For this purpose the valve 29 is connected to the throttle 5 by a link 30, or other means, in such relation that as the throttle opens the valve closes, or vice versa. Another important reason for this is, that as the pressure on the burner due to the pump tends to persist a certain time after the forced draft and the pump stop, it causes the burner flame to be more or less smoky, due to incomplete combustion with only natural draft, and by opening the auxiliary supply valve as soon as the forced draft ceases, the burner pressure may be quickly reduced to that of the auxiliary tank and thereby prevent smoking. Again the burner would consume more fuel than is necessary if the higher pressure were maintained when the delivery of steam from the boiler ceased. The quantity of air in the auxiliary tank and thereby prevent smoking, neglecting possible loss due to slight leakage or absorption, and hence, after the initial filling the hand pump need be seldom if ever, called into service. The demand for fuel depends upon the class of service, as to whether the stops are few or many and of long or short duration, for at such time the fire is in banked condition and draws its supply from the auxiliary tank. As the quantity of the fuel decreases, by reason of this consumption, the pressure on the remaining fuel in the tank, as indicated by the gage, becomes diminished. Hence, by observing the pressure gage the operator may ascertain at any time the approximate quantity of fuel in the pressure tank. When coasting, the throttle 5 is closed and the valve 29 open but the pump continues to operate because of its driving connection with the axle. The capacity of the auxiliary tank 12 is so much greater than the displacement of the pump plunger, that the pump under these conditions delivers fuel to the burner at substantially the pressure of the tank 12, any surplus fuel flowing into the tank and replenishing its supply after the loss sustained by feeding the burner during standstill. When the pressure falls below normal, it may be restored by recharging the tank with fuel. This I prefer to do by means of the power pump, and while the vehicle is

moving, preferably at times when the load is light, as in running on the level at low speed or coasting down grade. For this purpose I connect the delivery side of the pump or the main service pipe 20, with the auxiliary tank 70 by a supply pipe 31. This connection is controlled by a manually-actuated valve 32 which is adapted to be opened and closed as conditions require. I have indicated the valve diagrammatically, but in practice it 75 will be of such construction as to be capable of manipulation from the vehicle seat. This enables the operator to open and close the valve at any time without stopping the vehicle or dismounting.

In case the main tank becomes depleted when the vehicle is out on the road and inconvenient to a garage or other place where fuel can be obtained, the fuel in the auxiliary tank may be employed under such 85 emergency conditions so that the vehicle will not be stalled. For this purpose the fuel in the auxiliary tank can be supplied to the main tank by simply opening the valve 14 in the gravity feed pipe 13 so as to permit 90 the fuel to flow to the main tank by reason of the air pressure in the auxiliary tank. The fuel pump will continue to draw its supply from the main tank as usual.

In accordance with the provisions of the 95 patent statutes, I have described the principle of operation of my invention together with the apparatus which I now consider to represent the best embodiment thereof; but I desire to have it understood that the apparatus shown is only illustrative, and that the invention can be carried out by other means.

What I claim as new and aim to secure by Letters Patent of the United States, is,

1. In a fuel supply system, the combination of a burner, a source of fuel supply, a pump connected with the source and the burner for supplying fuel directly to the latter at service pressure, a motor for normally driving the pump, a receptacle adapted to receive fuel delivered by the pump and to hold it under a pressure lower than that due to the pump, and a controllable connection leading from the receptacle to the burner which connection is normally closed and is adapted to be opened to supply fuel to the burner to maintain the flame when the supply of energy for driving the pump motor is interrupted.

2. In a fuel supply system, the combination of a burner, a main supply tank subjected to a low pressure, a pump between the tank and the burner for increasing the pressure of the fuel to service pressure, an auxiliary tank subjected to a pressure above that of the main tank and lower than the normal burner pressure, and arranged to feed the burner when the pump pressure falls, and manually controlled means whereby the 130

pump is permitted to discharge fuel from the main to the auxiliary tank for recharging the latter.

3. In a fuel supply system, the combination of a burner, a main source of supply at substantially atmospheric pressure, a pump connected with the source and the burner for supplying fuel directly to the latter at high pressure, an auxiliary source of supply connected with the burner for supplying fuel thereto at low pressure, a controlled connection between the sources through which fuel may be fed by gravity from the main source to the other, and means for supplying fuel to the auxiliary source from the pump.

4. In a fuel supply system, the combination of a burner, main and auxiliary sources of fuel supply connected with the burner, means for increasing the fuel pressure between the main source and the burner, a connection between said means and the auxiliary source for re-charging said source by said means, and a fuel feed connection between the two sources through which fuel may be fed by gravity from the main to the auxiliary source.

5. In a supply system, the combination of a burner, main and auxiliary sources of supply connected in parallel relation with the burner, a gravity feed supply pipe between the sources, means for imparting an initial pressure to the auxiliary source of supply, a pump between the main source of supply and burner, and a controlled connection between the pump and the auxiliary source of supply for recharging the latter from the pump.

6. In a fuel supply system, the combination of a burner, a main tank, a supply connection between the tank and the burner, an auxiliary tank also connected with the burner, a pump in said supply connection which forces fuel from the main tank to the burner, means for re-charging the auxiliary tank from the pump, and conduits for delivering fuel from the auxiliary tank to the burner and to the main tank, one conduit also being arranged to feed fuel by gravity from the main tank to the auxiliary tank.

50. 7. In a fuel supply system, the combination of a burner, a main supply tank connected therewith, a pump for increasing the pressure of the fuel supplied by the tank to the burner, an auxiliary supply tank connected to the burner and subjected to a pressure which is less than the normal burner pressure, means causing the pump to discharge fuel into the auxiliary tank for the purpose of recharging it, and means admitting fuel to the burner from the auxiliary tank when the main supply is interrupted.

8. In a fuel system, the combination of a burner, a main tank, an auxiliary tank under pressure, supply connections between the tanks and burner for delivering fuel to it

from either of said tanks, a valved connection between the auxiliary tank and the main supply connection for recharging the tank, and means connecting the two tanks for permitting fuel to flow from one to the other 70 under certain conditions.

9. In a fuel supply system, the combination of a burner, a main tank, a supply connection between them, a pump included in the connection for increasing the pressure of the fuel supplied to the burner, an auxiliary tank also arranged to supply fuel to the burner and independently of the main tank, a manually controlled connection between the pump and the auxiliary tank through 75 which fuel to recharge the tank is forced by said pump, and a valve for controlling the flow of fuel between the auxiliary tank and the burner.

10. In a fuel supply system, the combination of a burner, a main tank, a pump tending to deliver fuel from the tank to the burner at substantially constant pressure, an auxiliary tank subjected to a pressure greater than that on the main tank and less than the 90 normal pressure on the burner, a controlled connection between the same and the burner, and means for opening communication between the delivery side of the pump and the auxiliary tank to permit the pump to charge 95 said tank, said communication being normally closed or shut off.

11. In a fuel supply system, the combination of a burner, a main tank, a pump which tends to deliver fuel from the tank to the burner at substantially constant pressure, an auxiliary tank connected with the burner, means for placing the latter tank under air pressure which is greater than the pressure on the main tank and less than the normal 100 pressure on the burner, means for delivering fuel from the pump to the auxiliary tank to charge said tank, and a valve for controlling the supply of fuel to the auxiliary tank 105 which is normally closed.

12. In combination, a boiler, a burner therefor, an engine, a throttle controlling the delivery of steam to the engine, a main source of fuel supply, an auxiliary fuel supply under pressure, a pump driven by the engine 115 for delivering fuel from the main source to the burner, two separate means for supplying fuel to the auxiliary source, one of which conveys fuel from the pump to said source, and means for supplying fuel to the burner 120 from the auxiliary source simultaneously with the cutting off of steam to the engine.

13. In combination, a boiler, a burner therefor, an engine, a throttle controlling the delivery of steam to the engine, a main 125 source of fuel supply, a pump for delivering fuel from said source to the burner, a regulator for the pump which tends to maintain the delivery of fuel at a constant pressure, an auxiliary tank connected with the burner, 130

a valve intermediate the auxiliary tank and burner operatively connected with the throttle, and a valved connection between the auxiliary tank and the delivery side of the 5 pump.

14. In combination, a boiler, a burner therefor, an engine, a throttle controlling the delivery of steam to the engine, a main source of fuel supply, a pump driven by the 10 engine for delivering fuel from said source to the burner, a regulator for the pump which tends to maintain the delivery of fuel at a constant pressure, an auxiliary tank connected with the burner, a valve intermediate 15 the auxiliary tank and the burner operatively connected with the throttle, a gravity feed-pipe between the main tank and auxiliary tank, a valve therefor, a connection between the auxiliary tank and the delivery 20 side of the pump for permitting the pump to charge said tank, and means for regulating the flow of fuel through said connection.

15. In a fuel supply system for automobiles, the combination of a burner, main and 25 auxiliary sources of fuel supply which are adapted to supply fuel independently to the burner, a power pump arranged between the main source and the burner which while the automobile is running, is adapted to operate 30 and supply fuel to the burner, a connection between the discharge side of the pump and the auxiliary source for recharging the latter from the pump while it is in operation, and a manually operated valve for controlling 35 said connection.

16. In a fuel supply system for automobiles, the combination of a steam or other vapor generator, an engine for driving the vehicle, a burner for heating the generator, 40 main and auxiliary sources of fuel supply separately connected with and delivering fuel to the burner, a pump driven by the engine which supplies fuel from the main source to the burner, a connection between the 45 delivery side of the pump and the auxiliary source which is adapted to convey fuel from the pump to the source for recharging, and a manually operated controlling valve in said connection.

50 17. In a fuel supply system for automobiles, the combination of a steam or other vapor generator, an engine for driving the vehicle, a throttle for controlling the supply of vapor to the engine, a burner for heating 55 the generator, main and auxiliary sources of fuel supply connected with the burner to supply the same, a pump driven by the engine which supplies fuel from the main source to the burner, a supply connection between the delivery side of the pump and the auxiliary source for refilling the latter from the pump, a manually controlled valve controlling said connection, a valve for controlling the supply of fuel between the auxiliary 60 tank and the burner, and means for simul- 65

taneously opening the said latter valve while closing the throttle or vice versa.

18. In a fuel supply system for automobiles, the combination of a steam or other vapor generator, an engine for driving the 70 vehicle, a throttle for controlling the supply of vapor to the engine, a burner for heating the generator, main and auxiliary sources of fuel supply connected to the burner for supplying fuel thereto, a pump driven by 75 the engine which supplies fuel from the main source to the burner, means for maintaining the delivery of the pump at substantially constant pressure, a connection between the delivery side of the pump and 80 the auxiliary source for refilling the latter from the pump, a manually controlled valve controlling said connection, a valve for controlling the supply of fuel between the auxiliary tank and the burner, and means for 85 simultaneously opening the said latter valve while closing the throttle or vice versa.

19. In a fuel supply system for automobiles, the combination of a steam or other vapor generator, an engine for driving the 90 vehicle, a throttle for controlling the supply of vapor to the engine, a burner for heating the generator, main and auxiliary sources of fuel supply connected to the burner, a pump driven by the engine which supplies 95 fuel from the main source to the burner, a variable stroke mechanism for the pump for maintaining the delivery thereof at substantially constant pressure, a connection between the delivery side of the pump and the 100 auxiliary source for refilling the latter from the pump, a manually controlled valve controlling said connection, a valve for controlling the supply of fuel between the auxiliary tank and the burner, and means for 105 simultaneously opening the said latter valve while closing the throttle or vice versa.

20. In a fuel supply system, the combination of a boiler, a burner for heating the boiler, an engine receiving steam from the boiler, a throttle valve for controlling the supply of steam from the boiler to the engine, a main fuel supply tank, a fuel pump driven from the engine, a supply conduit between the main tank and the pump, a delivery conduit between the pump and the burner, a valve in said delivery conduit adjacent the burner, an auxiliary tank arranged at a lower level than the main tank, a conduit extending between the two tanks 115 for feeding fuel by gravity from the main to the auxiliary tank, a valve in said feeding conduit, a conduit leading from the delivery conduit at a point between the pump and the valve in said conduit to the auxiliary tank for re-charging said tank with fuel under pressure from the pump, a manually controlled valve in the re-charging conduit, a conduit for supplying fuel from the auxiliary tank to the delivery conduit at a 120 125 130

point between the pump and the valve in
said delivery conduit, a valve in the last
mentioned conduit, and a connection be-
tween said valve and the throttle valve
5 which opens said valve when the throttle
valve is closed and vice versa.

In witness whereof, I have hereunto set

my hand this twenty-eighth day of July,
1904.

HERMANN LEMP.
